TOILET TISSUE HOLDER

Elmer H. Lindenmeyer, Maywood, Ill.

Application January 2, 1952, Serial No. 264,419

8 Claims. (Cl. 242—55.2)

1

My invention relates to holders for toilet and other types of household tissue, and more particularly to the facility for mounting and removal of the tissue roll and the means for applying a friction factor thereto. Such holders as I have found on the market require manipulation or the partial dismantling of the holder in order to mount or remove a roll of tissue, and others allow the roll an excessive amount of freedom, so that it gains a tendency to spin when tissue is drawn, to the end that an over-supply is dispensed. In order to overcome these deficiencies, it is one object of the present invention to provide a holder which needs no handling or attention of any kind while mounting or removing the tissue roll.

A further object is to provide a holder of the type adapted to receive the tissue roll from one end which incorporates a stop device to prevent the accidental dislocation of the roll from the holder after the roll has once been mounted on the same.

Another object is to construct the holder with a roller weight element designed to deter the excessive rotation of the roll and eliminate the tendency of the same to spin.

An additional object is to design the novel holder along lines of simplicity and durability.

With the above objects in view, and any others which may suggest themselves from the description to follow, a better understanding of the invention may be had by reference to the accompanying drawing, in which—

Fig. 1 is a top plan view of the holder, on a reduced scale, as mounted on a bathroom wall;

Fig. 2 is a full-size section on the line 2—2 of Fig. 1, showing the manner in which the tissue roll is applied by means of finely-dotted lines;

Fig. 3 is a bottom plan view of the holder, partly broken away; and

Fig. 4 is a front elevation.

In accordance with the foregoing, specific reference to the foregoing indicates the main element of the holder as an elongated cylindrical housing 10 which is designed to occupy a horizontal position. One end of the housing, which may be considered as the rear end, is thickened as indicated at 12 and tapped in the center to receive a screw 16. The housing 10 is supported by a horizontal bracket of L-shape. One arm 18 of this bracket is short and receives screws or other means 19 to fasten it to a wall, as shown in Fig. 1. The other arm 20 of the bracket extends forwardly from the wall to receive the end 12 of the housing 10 as shown in Fig. 2, the screw 16 being passed through the bracket arm 20 into the said end to secure the housing to the bracket.

The front end 25 of the housing 10 is of thick construction and only extends about half-way to the bottom; and such end projects from the top 60

of the housing with a lug 26. On the inside the front end 25 is recessed from the rear and bottom at a central point, as indicated at 27, and receives a horizontal cross-pin 30.

The bottom of the housing 10 is open and accommodates a rearwardly inclined arm 35. The frontal portion of the arm is enlarged with a head 36 which is disposed in the front-end recess 27 and journaled on the cross-pin 30. The upper portion of the head 36 is rounded and the contiguous wall of the recess 27 shaped correspondingly to facilitate the upswing of the arm from the position shown in Fig. 2; but the front ends of the head 36 and the recess are in flat contact to check the downswing of the arm from the position shown.

The arm 35 is reduced at the rear to the form of a rod 38 to journal a pear-shaped roller 39, the rod being enlarged with a terminal head 40 for the retention of the roller.

The diameter of the housing 10 is such as to facilitate the mounting of a conventional toilet tissue roll 42 on the housing in the position indicated by full lines in Fig. 1 and long dotted lines in Fig. 2. It is understood that in the case of paper towels the housing would be dimensioned accordingly. The tissue roll is designed to be mounted from the front end of the housing, being raised sufficiently to clear the frontal lug 26 as it is advanced, according to the finely-dotted lines in Fig. 2. When the roll is fully mounted on the housing, it drops to a position behind the lug 26, which now serves as an abutment to check the return movement of the roll. The latter is now in the position of use.

The advance of the tissue roll as just described causes its core 43 to first meet the conical wall of the roller 39. However, due to the pivotal suspension of the roller the pressure of the roll 40 will cause the roller to yield in an upward direction and clear the way for the continued advance of the roll. Thus, when the latter becomes fully mounted, the roller 39 rests in the bottom of the core 43, serving as a deterrent or friction factor to keep the roll from spinning when tissue is drawn therefrom. The roller is preferably of metal, and of sufficient weight to accomplish this purpose; and the lower swinging limit of the roller places it in the proper position to be raised by the tissue roll with a minimum amount of effort.

It will now be apparent that the tissue roll mounted as described is a very handy facility. The bracket 20 supports the roll close to the wall, so that it may not project too far into the room space. Further, the tissue roll is mounted from one end only and without necessitating any handling or taking apart of the holder. The direction of mounting approach shown in Fig. 1 is from the left-hand side. However, should it be more convenient to mount the tissue roll from

the right-hand side, the screw 16 of the bracket may be loosened slightly, the bracket rotated a half-turn, and the assembly swung around to the position indicated by finely-dotted lines in the same figure. It is further apparent that the mounting of the tissue roll may be done with only one hand; and that no further handling, adjustment or other attention is required when the roll has been fully mounted on the holder. Conversely, in case the core remnant of a tissue roll is to be removed, it is only necessary to raise it from the bottom at the front until it clears the lug 26, when it may be withdrawn quickly, placing the holder in readiness for the mounting of the next roll. Further, the friction roller 38 is freely rotatable and therefore imposes no dragging or excessive amount of friction on the tissue roll; and the weight of the roller is calculated to correspond to the amount of deterring influence required for the tissue roll. Finally, it is apparent that the holder is made up of few parts which are simple and rugged, whereby to make the cost of producing the holder reasonable and render it durable over a long period of use.

While I have described the invention along specific lines, various minor changes or refinements may be made therein without departing from its principle, and I reserve the right to employ all such changes and refinements as may come within the scope and spirit of the appended claims.

I claim:

1. A holder for a tubular roll of paper comprising a member designed to be positioned horizontally as a core for the rotatable support of the roll, the member allowing access to the bottom of the internal wall of the roll, and means to control the rotation of the roll comprising an arm connected to the member and freely movable toward said bottom, and a roller journaled on the arm in frictional engagement with such bottom.

2. A holder for a tubular roll of paper comprising a member designed to be positioned horizontally as a core for the rotatable support of the roll, the member allowing access to the bottom of the internal wall of the roll, and means to control the rotation of the roll comprising an arm connected to the member and freely movable toward said bottom, and a weighted roller journaled on the arm in frictional engagement with such bottom.

3. A holder for a tubular roll of paper comprising a member designed to be positioned horizontally as a core for the rotatable support of the roll, and means to control the rotation of the roll comprising an arm pivoted horizontally to the member with one end portion, and a roller journaled on the other end portion of said arm and resting by its weight in frictional engagement with said bottom.

4. A holder for a tubular roll of paper comprising a member designed to be positioned horizontally as a core for the rotatable support of the roll, and means to control the rotation of the roll comprising an arm pivoted horizontally with one end portion to one end of the member, and a roller journaled on the other end portion of said arm and resting by its weight in frictional engagement with said bottom.

5. A holder for a tubular roll of paper comprising a member designed to be positioned horizontally as a core for the rotatable support of

the roll, the member being attachable with one end to a support and allowing access to the bottom of the internal wall of the roll, and means to control the rotation of the roll comprising an arm pivoted horizontally to the free end of the member with one end portion, and a roller journaled on the other end portion of said arm and resting by its weight in frictional engagement with said bottom.

6. A holder for a tubular roll of paper comprising a member designed to be positioned horizontally as a core for the rotatable support of the roll, the member being attachable with one end to a support and allowing access to the bottom of the internal wall of the roll, and means to control the rotation of the roll comprising an arm pivoted horizontally to the free end of the member with one end portion, a roller journaled on the other end portion of said arm and resting by its weight in frictional engagement with said bottom, said free end being formed with a vertical recess in which the first-mentioned end of the arm is disposed, and a cross-pin passing through said recessed end and the related end of the arm to form the pivot of the latter.

7. A holder for a tubular roll of paper comprising a member designed to be positioned horizontally as a core for the rotatable support of the roll, the member being attachable with one end to a support and allowing access to the bottom of the internal wall of the roll, and means to control the rotation of the roll comprising an arm pivoted horizontally to the free end of the member with one end portion, a roller journaled on the other end portion of said arm and resting by its weight in frictional engagement with said bottom, and a stop element checking the down-swing of the arm at a point facilitating the upward crowding and clearing of the roller by said bottom when the roll is mounted on the member from said free end.

8. A holder for a tubular roll of paper comprising a member designed to be positioned horizontally as a core for the rotatable support of the roll, the member being attachable with one end to a support and allowing access to the bottom of the internal wall of the roll, and means to control the rotation of the roll comprising an arm pivoted horizontally to the free end of the member with one end portion, a pear-shaped roller journaled on the other end portion of said arm and resting by its weight in frictional engagement with said bottom, the pivoted end portion of the arm meeting the back of the recess as a stop for the arm's downswing at a point facilitating the climbing of the conical surface of the roller and the clearing of the latter by said bottom when the roll is mounted on the member from said free end.
